UNITED STATES PATENT OFFICE.

GEORGE W. KORN, OF NEW YORK, N. Y.

DESIGN FOR A KNIFE-HANDLE.

SPECIFICATION forming part of Design No. 14,929, dated April 1, 1884.

Application filed October 25, 1883. Term of patent 7 years.

To all whom it may concern:

Be it known that I, GEORGE W. KORN, a citizen of the United States, residing in the city of New York, in the State of New York, have invented and produced a new and useful and original Design for Knife-Handles, of which the following is the specification, reference being had to the accompanying drawings, forming part thereof.

10 Figure 1 is a side view of my design. Fig. 2 is a back view of same.

One end of the handle is formed with a straight line of the requisite length as a base, as at *a*, showing the depth of the handle at this 15 end, the edges of the handle starting from each end of this base-line with a rapidly-diverging course of about fifteen degrees until they reach the points 1 and 2, respectively, when they begin to converge in a much less 20 degree until the distance between them is equal to the length of the base-line whence they started, at which point the line 3 again diverges more rapidly than when it did at first from the

base-line, and continues in this course until it reaches the point 4, when, with a returning 25 rounded curve and a slightly-descending scalloped course, it meets the other line with a rounded corner. At a short distance from this last end described a line crosses from one line to the other. On the line *e* at its upper 30 end, and nearly perpendicular to it, starts the line *a* and continues until it reaches to *b*, where it turns with a rounded corner and intersects the line *e* at *c*. A second line, *d*, starts from line *e* below line *a*, and with a curved and direct course it meets the line *e* at *i*. 35

The contour shown and described presents a shape and design for a knife-handle unique and pleasing to the eye.

I claim—

10 The design for a knife-handle, herein shown and described.

GEORGE W. KORN.
